CLAIM

The ornamental design for a delivery cabinet, as shown and described.

DESCRIPTION

FIG. 1 is a front perspective view of a delivery cabinet showing our new design;

FIG. 2 is a front view thereof;

FIG. 3 is a left side view thereof, the right side being a mirror image thereof; and,

FIG. 4 is a top view thereof.

The broken lines depicting five regions within the shaded area and the remainder of the delivery cabinet form no part of the claimed design.
